EZECHIEL WEINTRAUB, OF LYNN, MASSACHUSETTS, ASSIGNEE TO GENERAL ELECTRIC COMPANY, A CORPORATION OF NEW YORK.

ELECTROLYTIC METER.

1,069,211.

Specification of Letters Patent. Patented Aug. 5, 1913.

Application filed February 14, 1910. Serial No. 543,755.

To all whom it may concern:

Be it known that I, EZECHIEL WEINTRAUB, a citizen of the United States, residing at Lynn, county of Essex, State of Massachusetts, have invented certain new and useful Improvements in Electrolytic Meters, of which the following is a specification:

My invention relates to meters for measuring the consumption of electric current in a circuit, that depend for their action upon the decomposition of an electrolyte by the current. Meters of this class have been heretofore proposed in which the anode is a body of mercury, but it has been found difficult to maintain them in proper working order owing to imperfect circulation in the electrolyte, that tends to permit the establishment of a counter-electromotive force in the meter, and to incomplete agglomeration of the mercury deposited from the solution, etc.

My invention aims to eliminate these objections and produce a simple, reliable and stable instrument.

The meter which I have invented may take various forms and those which I shall illustrate and describe are only some forms which have been found to be satisfactory.

In general, my meter consists of a suitable vessel to contain the electrolyte, with a fall tube at the bottom to collect the deposited mercury, and a container for the mercury anode suspended in the upper part of said vessel with a hermetically tight joint between them; the lower end of said container being closed by a diaphragm of a suitable substance possessing osmotic properties and having sufficient strength to sustain the weight of the mercury and also capable of resisting the action of the electrolyte. I prefer to use for this purpose a piece of gold beater's skin.

In the accompanying drawings, Figure 1 is a vertical view, partly in section, of one form of my meter; Fig. 2 is a similar view of a modification of Fig. 1; and Fig. 3 is a view in perspective on a larger scale of a form of cathode.

The theory of these mercury meters is well known, and it is not necessary to go into this at any length, but merely to say

that the action of the meter depends upon the deposition of mercury from an electrolyte containing a mercury salt in solution; the decrease in mercury being made up constantly by solution from the anode. In my meter this solution takes place through the membrane or diaphragm.

Referring first to Fig. 1, the electrolyte 1 is held in a glass vessel 2 from whose lower end depends the fall tube 3. This fall tube is made of a smaller diameter and graduated, as shown, to enable the deposited mercury to be readily measured, the fineness of reading depending upon the diameter of the tube. A cross-section of this tube has not been illustrated, since it may be of any desired or suitable configuration. The upper end of the vessel 2 has a throat 4, preferably somewhat conical, to receive a tapering glass container 5 in which the mercury anode 6 is inclosed. The upper end of throat 4 is formed with a projecting lip 4' so that a suitable sealing substance may be poured in this lip to firmly attach the container to the vessel. The joint between the vessel 2 and the container 5 is made air-tight, preferably by forming a ground joint where the two come in contact. The upper end of the container is closed and a leading-in wire 7 passes into the container and extends down into the mercury for making connections with the circuit to be measured. The lower end of the container is open and has a flaring or flanged construction, affording a convenient means for securing the membrane or diaphragm 8, which is preferably composed of gold beater's skin and is drawn tightly over said flange and suitably secured in place, as by a tie-wire 9 of platinum. At a little distance below the membrane is the cathode, which may consist of a ring 10 of glass covered on its outside surface by a thin sheet or foil of platinum to which leading-in wire 11 is connected. The ring is conveniently supported by an arm 13 projecting from the wall of the vessel 2. In the wall of the container there is formed an opening 14 which ends in a tube 15, and forms a passage through the wall of the container into vessel 2. This passage is so positioned that the volume of the con-

tainer above the passage is greater than that of the volume of the container below the passage. The object of this passage is to return to the container the mercury which has been deposited in the fall tube, and this return may be effected by inverting the meter so that the mercury will flow into what is normally the top of the meter and through the passage into the container. 10 The upper portion of the container is made sufficiently large to hold all the mercury which may be used with the meter.

Fig. 2 shows a modification of Fig. 1. The modification consists in forming the 15 anode container with a number of branches similar to the single branch shown in Fig. 1. These branches have open lower ends each covered by an osmotic membrane 8' so that the container is provided with a 20 multiplicity of these membranes. The advantage of this form of construction over that shown in Fig. 1 is that each membrane may be made to have a smaller surface so that it will have great mechanical strength. 25 As a number of such membranes are used, the total surface of the membranes will be larger for greater mechanical strength than if only one membrane were used, and thus the polarization at the anode is decreased. 30 since the polarization is smaller the larger the surface. In this form of meter I have illustrated a different form of cathode which is shown on a larger scale in Fig. 3. This cathode may be made of various sub- 35 stances, such, for example, as Acheson graphite, which I have used with success. The cathode consists of a cylindrical member 16 formed of graphite or other suitable substances and attached by an insulated 40 member 17 to the wall of vessel 2. A conductor may be extended along this member 17 and connected to the leading-in wire 12.

My osmotic membrane solves several of the problems which have heretofore been 45 troublesome in this class of meters. It makes the reduction in the volume of the anode immaterial, as a certain definite surface is always in communication with the electrolyte. It permits the placing of the 50 anode directly above the cathode and reduces the distance between them to a very small value so that the difference in concentration of the solution due to the electrolytic action is very slight. It secures a good 55 circulation of the solution by the action of gravity, the rich liquid falling from the anode to the cathode and the poor liquid rising from the cathode to the anode. In this connection it should be stated that in 60 order to get the best results the electrolyte should be free from both acid and alkaline solutions or solutions that are liable to give, in the course of operation, slightly acid or alkaline reactions. One of the reasons for

this is that a solution which is not neutral 65 exerts after a long period a weakening action on the membrane. I have found that a suitable substance for the electrolyte may be a solution of mercuric chlorid and potassium sulfocyanate or a solution of the 70 double sulfocyanate of potassium and mercury; the essential characteristic of the solution being that hydrolysis is practically absent.

I have described and illustrated my pres- 75 ent invention as embodied in a particular form of meter. The features of construction of this particular meter are claimed in the patent granted to me October 24, 1911 and numbered 1,006,612.

What I claim as new and desire to secure by Letters Patent of the United States, is,—

1. An electrolytic meter having a mer- 80 cury anode, an osmotic membrane separat- 85 ing it from the electrolyte, and an electro- 90 lyte containing potassium sulfocyanate.

2. An electrolytic meter having a mer- 95 cury anode, a membrane of gold beater's skin separating it from the electrolyte, and an electrolyte containing potassium sulfo- 100 cyanate.

3. An electrolytic meter comprising a vessel for the electrolyte having a tapered throat, a tapering container for the mercury anode fitting hermetically into said throat, 95 and an osmotic membrane closing the lower end of said container.

4. An electrolytic meter comprising a ves- 100 sel for the electrolyte, a container for a mercury anode depending from the upper part of said vessel provided with a passage through its wall into the vessel, and an os- 105 motic membrane closing the lower end of the container.

5. An electrolytic meter comprising a ves- 110 sel for the electrolyte, a closed container for the mercury anode depending from the upper part of said vessel provided with a pas- 115 sage through its wall into the vessel positioned so that the volume of the container above the passage is greater than the volume below the passage, and an osmotic mem- 120 brane closing the lower end of the container.

6. An electrolytic meter having a mer- 125 cury anode and comprising, a vessel for the electrolyte, a container for the mercury anode depending from the upper part of said vessel and provided with a plurality of branching tubes, an osmotic membrane cov- 130 ering the lower end of each of said branch- 135 ing tubes, and a coöperating cathode in said vessel.

7. An electrolytic meter having an anode of mercury, an electrolyte, and a membrane of gold beater's skin separating the mer- 140 cury and electrolyte.

8. An electrolytic meter having a mer- 145 cury anode comprising, a vessel for the elec-

trolyte, a container for the mercury anode depending from the upper part of said vessel, a plurality of branch tubes depending from said container, an osmotic membrane covering the lower end of each branch tube, and a passage through the wall of said container and communicating with said vessel.

In witness whereof, I have hereunto set my hand this eleventh day of February, 1910.

EZECHIEL WEINTRAUB.
